MOBILE COOKING TRAILER

Kenneth Beasley, 2141 NW. 33rd.,
Oklahoma City, Okla. 73112

Filed July 15, 1974, Ser. No. 488,675

Term of patent 14 years

Int. Cl. D7—02; D12—10

U.S. Cl. D7—108

FIG. 1

FIG. 2

FIG. 3

FIG. 4

FIG. 5

FIG. 6

FIG. 1 is a side elevational view of a mobile cooking trailer showing my new design;

FIG. 2 is a top plan view thereof;

FIG. 3 is a front elevational view thereof;

FIG. 4 is a side elevational view thereof opposite to that shown in FIG. 1;

FIG. 5 is a bottom plan view thereof; and

FIG. 6 is a rear elevational view thereof.

The crossing pattern shown on the top and bottom of the canopy in FIGS. 2 and 5 is understood to be repeated uniformly throughout the canopy.

I claim:

The ornamental design for a mobile cooking trailer, substantially as shown and described.
